WASHING MACHINE

William W. Russell, Brookline, Mass.

Application October 15, 1936, Serial No. 105,690

1 Claim. (Cl. 68—184)

This invention relates to washing machines. One of the objects of this invention is to provide a washing machine having no moving parts within the washing receptacle to damage the goods being washed.

Another object of this invention is to provide a washing machine so constructed that the use of a relatively small amount of power will be sufficient to adequately agitate and wash the clothes.

Still another object of my invention is to provide a washing machine in which the clothes are agitated and washed by the movement of the water alone and so constructed that the clothes will continue in rotation without the formation of dead spots.

Another object of my invention is to provide a washing machine that is adapted to wash the most delicate garments without danger of damage thereto.

Referring to the drawings:

Fig. 1 is a front elevation;

Fig. 2 is a side elevation;

Fig. 3 is a vertical section on the line 3—3 of Fig. 2 of the receptacle of the machine with the pump and motor shown in elevation;

Fig. 4 is a fragmentary view similar to Fig. 3 showing diagrammatically the general character of the movement of the water and contents;

Fig. 5 shows the receptacle provided with a cover.

Heretofore it has been attempted to construct a washing machine which will operate without the need of any oscillating or rotating vanes or other members within the receptacle of the machine. One of the reasons for constructing a machine of this character is to prevent damage to fabrics which is often caused in those machines having moving members within the receptacle.

In all of the prior art, however, as far as I am aware, washing machines which have been operated by means of a stream of water discharged into the receptacle have failed in operation because of the failure of the clothes and the water to keep moving continuously. This has been due either to the particular shape of the receptacle, the position of the inlet, or the position of the outlet with respect to the inlet.

In the case where washing machines having cylindrical receptacles have been used, as shown, for example, in the patent to Lombard, No. 944,736, the rotation and washing have been hindered because of the excessive friction of the clothes with the square ends of the receptacle coupled with the inability of the clothes to shift position so that all parts may be engaged by the jets. In

the case of those washing machines of the type having a container in which the bottom portion was hemispherical, as shown, for example, in the patent to Lombard No. 1,411,286, the rotation of the clothes and water has been impeded, and, in many cases prevented by the clothes tending to collect in the dead spots that inevitably form at the top of the water in this type of receptacle.

In the case of the cylindrical or hemispherical receptacle used by the prior art it will also be found that the water has been introduced into the receptacle through nozzles projecting into the receptacle. Nozzles so positioned engage the clothes during the latter's movement thereby making damage to the clothes possible.

Referring now to Fig. 1 it will be seen that my washing machine consists in general of a spherical receptacle 2 with an opening 3 at the top carried by any suitable supporting frame which in this case comprises legs 4 connected with base 6. The opening 3 must be small enough so that the receptacle remains substantially spherical.

Positioned on base 6 is an electric motor 8 which, by means of shaft 10, drives the centrifugal pump 12.

On the lower part of receptacle 2 is a chamber 14 connected with the interior of the receptacle by the perforations 16 shown in Figs. 3 and 4. An outlet 18 extends from chamber 14 to the centrifugal pump 12. From the discharge side of the pump 12 extends the pipe 20 which terminates at the entrance port 22 in receptacle 2 as shown in Figs. 3 and 4. Port 22, it will be observed, is flush with the inside of my spherical receptacle.

It will be noted that port 22 is positioned somewhat above the middle of the receptacle and the angle of pipe 20 with relation to port 22 is such that water entering receptacle 2 from pipe 20 does not enter tangentially but rather in a more inwardly direction. The water enters in the plane of a great circle of the sphere, preferably, but at the angle of a chord which would subtend an angle in the neighborhood of 60 to 90 degrees. The reason for this will appear hereafter. As can be seen from Fig. 2 water entering the receptacle from pipe 20 will travel in a vertical plane but at the angle generally shown by the arrows 24 in Fig. 4.

Associated with the outlet 18 is a drain cock 26.

The operation of my washing machine is as follows. The receptacle 2 is filled until the combination of material to be washed and the water rises approximately to the line 28 shown in Fig. 4.

It is essential that the receptacle be substantially full in order that proper rotation of the water

and clothes will be secured. That is to say, the total mass within the receptacle must be practically a complete sphere. The machine will not operate if it is only partially filled.

- 5 In the event that only a small amount of clothes are to be washed there must still be enough water added to bring the level to the line 28 to round out the sphere. On the other hand if a large quantity of clothes are to be washed, 10 the clothes may be inserted first until they comfortably fill the receptacle and then water is added until it reaches the level of line 28. However, the order of introducing the clothes and water is immaterial so long as the final level of 15 the contents results in a substantially spherical mass.

A suitable amount of soap powder or soap flakes to emulsify the dirt in the clothes is introduced as well. At this point the machine is 20 ready to be started.

Motor 8 is turned on to cause the operation of pump 12. The water in the receptacle 2 is sucked downwardly through the perforation 16 to chamber 14 through pipe 18 into the pump and discharged from the pump through pipe 20 passing thereby to the entrance port 22. The water enters the receptacle through port 22 in the direction of arrows 24 shown in Fig. 4 and at a considerable velocity. The velocity of the water 30 coupled with the direction at which it is introduced into the receptacle causes the entire mass of water and clothes to start to revolve. After a few seconds the rate of rotation reaches a maximum and continues thereafter as long as the pump 35 12 remains in operation.

It will be apparent that the water is continuously circulated from the receptacle 2 through the perforations 16 to the tank 14, thence to the pump 12 and back into the receptacle through 40 pipe 20 and port 22. The axis of rotation of the mass of water and clothes will be, in the case shown, a line extending through the centre of the receptacle and vertical to the plane in which the water is introduced through pipe 20. Thus, 45 in this case, the axis of rotation will be the horizontal line A—A extending through the centre of the receptacle as in Fig. 2.

The plane in which the water is introduced may be varied from the vertical if desired but I 50 have found that rotation of the mass is facilitated if the arrangement is as shown. The angle at which the stream is directed through the wall of the receptacle as indicated by arrows 24 in Fig. 4 may be varied within reasonable limits but if 55 the water enters at an angle closely approximating the tangential, rotation of the mass is hampered as the water does not sufficiently impinge on the clothes thereby diminishing the rotative effect. On the other hand if the entering stream is 60 directed too much toward the centre of the receptacle the effective lever arm is reduced so that again the rotative effect is greatly diminished.

A major distinguishing feature of my washing machine over the prior art is the spherical receptacle which causes all parts of the moving mass to continually change direction thus producing true rotation. At the same time, since the receptacle is a sphere, the mass of clothes while rotating on the horizontal axis is continually 65 shifting its plane of rotation a trifle one way or the other as the water impinges on different portions of the clothes as they move by. In this way, in the course of the time required for proper washing, the clothes entirely shift their position 70 within the receptacle so that all portions at one

time or another will rotate in the plane of the sections shown in Figs. 3 and 4, to receive the direct effect of the stream entering through port 22. In this way all portions of the clothes are brought into contact with the impinging stream 5 so that the clothes are thoroughly washed.

Likewise all of the clothes in due course pass by the perforations 16. As the water is sucked through these perforations it is also drawn through the clothes adjacent thereto so that excellent cleansing is secured.

Due to the fact that the rotating mass is substantially a sphere the water and clothes during their movement may rise above the opening 3 of the receptacle to follow the course indicated by 15 the arrow 32. Due to the surface tension of the water coupled with the speed at which the mass rotates the water does not overflow at the opening but instead continues on its course as indicated to stay within the receptacle. Of course there is 20 some slight splashing and if this is found objectionable a cover 34 may be positioned on the machine during operation. It will be noted, however, that the cover is of the same curvature as the rest of the sphere and the movement of the 25 mass is in no way impeded thereby.

It is particularly desired that the absence of dead spots in the washing operation of my machine be noted. That is to say the entire mass is rotated in an endless path, all portions during 30 the rotation staying a constant distance from the axis of rotation. This promotes smooth and continuous action as no portion of the clothes or water departs from its regular course. The ability to keep all portions moving at a uniform speed 35 and in a circular course is one of the marked advantages of my machine over the art. An examination of all of the earlier machines in which the clothes were moved by the impact of a stream of water shows clearly that the path of movement of the entire mass of water and clothes 40 was not symmetrical with respect to any selected axis of rotation.

Because the opening to my receptacle 2 is small the clothes and water constitute substantially a 45 sphere and as soon as rotation begins the sphere is completed by the mass rising above the opening as indicated by arrow 32.

While the foregoing is a description and explanation of a preferred form of my invention I wish 50 it to be distinctly understood that I do not intend to be limited thereby but only by the appended claim.

I claim:

A washing machine, comprising a substantially 55 spherical receptacle having a completely unobstructed interior, said receptacle having a bottom outlet comprising a plurality of holes through the bottom of said receptacle, said holes covering a relatively large area, a single inlet flush with the 60 inner side of said receptacle and directed at said outlet but remote therefrom, a conduit including a pump connecting said outlet and inlet to circulate water in said receptacle, said receptacle adapted to hold textiles, that may be placed in said receptacle, in unobstructed ball-like form while said textiles are rotating within said receptacle by 65 said circulating water, the area covered by said outlet holes being sufficiently great so that all of the textiles on which incoming water impinges 70 will pass thereover immediately thereafter whereby a quick reversal of water travel through said textiles may be secured.
